UNITED STATES PATENT OFFICE.

ISRAEL LEVI KING, OF BOSTON, MASSACHUSETTS.

RAIL-JOINT.

1,380,976.

Specification of Letters Patent. Patented June 7, 1921.

Application filed October 7, 1920. Serial No. 415,812.

To all whom it may concern:

Be it known that I, ISRAEL LEVI KING, a citizen of the United States of America, residing at Boston, in the county of Suffolk and State of Massachusetts, have invented new and useful Improvements in Rail-Joints, of which the following is a specification.

The invention seeks to provide, as its 10 principal object, a rail joint whereby the connecting ends of adjoining rail sections are connected together without the use of angle plates or bolts.

A further object of the invention is to 15 provide a rail joint of this character which is simple in construction, strong and effective in operation and inexpensive to manufacture.

Still other and further objects will appear as the invention is set forth in detail 20 in the following description.

To the exact construction in which it is shown and described, the invention is not 25 to be restricted. The right is reserved to make such changes or alterations as the actual reduction to practice may demand, in so far as such changes or alterations are comprehended in spirit by the annexed claim.

30 In the accompanying drawings:

Figure 1 is a perspective view of the improved rail joint,

Fig. 2 is a section on the line 2—2 of 35 Fig. 1,

Fig. 3 is a section on the line 3—3 of Fig. 1,

Fig. 4 is a perspective view of the end 40 of one of the sections forming the joint inverted,

Fig. 5 is a perspective view of the end 45 of the coöperating section.

Referring to the drawings, there are shown, the connecting ends of two rail sections A and B. The two sections at their 50 connecting ends are made thicker in the web than elsewhere along their lengths, and these thickened portions of the two sections are designed to overlap in effecting the connection between them.

The tread and a part of the web are removed from the end of the section A, leaving 55 a base longitudinal projection 1 which is relatively narrow as compared with the width of the base. This projection 1 is pro-

vided at its free end with lateral projections 55 2 and at points intermediate between the projections 2 and the body of the rail, the base projection 1 is further provided with lateral projections 3, these latter as well as the lateral projections 2 simulating the 60 base of the rail body both in dimensions and shape.

To provide for connection with the section A, the connecting end of the section B is slotted longitudinally, leaving a slot 4 65 opening through the base. The section B is also slotted transversely across the slot 4, leaving the transverse recesses 5 and 6 whose depth is equal to the depth of the slot 4 and whose widths are equal to the 70 lengths of the lateral projections 2 and 3, the slot 4 being of a width equal to the width of the base projection 1.

In attaching the two sections together, the section A is first set on the ties by appropriate spikes and the section B thereafter connected with it, the base projection 1 entering the slot 4 and the lateral projections 2 and 3 entering the transverse recesses 5 and 6 respectively. The joint itself is made 75 secure with the tie by spiking the section B to the tie at those portions of the base flange of the section B standing between the transverse recesses 5 and 6 and the recess 6 and the end of the section. Thus the section B being secured to the tie at the joint, 80 overlaps and holds in place the section A. 85

It may be observed that the joint provides for the effective interconnecting of the ends of adjacent rail sections without the 90 use of angle plates or bolts therefor. It will also be observed that the interconnecting ends of the sections are so formed that they may be easily made, the formation of the peculiar shaped end of each section being obtainable by a drop forging process or 95 they may be also milled in the rails after the sections are rolled, thus providing an effective joint by a comparatively easy means of manufacture.

The invention having been described, what is claimed as new and useful is:

In a rail joint, the combination of two rail sections having interconnecting ends, the one section having a portion of its tread 105 removed to provide a longitudinal base projection, the said base projection having lateral projections at its free end and further

lateral projections at intermediate positions between the first said lateral projections and the body portion of the rail, the longitudinal base projection being relatively narrow as compared with the width of the base of the section, the other section being provided with a longitudinal slot opening through its

base and being further provided with transverse slots across the longitudinal slot, whereby the longitudinal base projection 10 may rest in the longitudinal slot and the lateral projections rest in the transverse slots.

In testimony whereof I affix my signature.

ISRAEL LEVI KING.
